UNITED STATES PATENT OFFICE.

WALTER A. DORSEY, OF COLUMBUS, OHIO, ASSIGNOR TO THE BOINNEY-FLOYD COMPANY,
OF COLUMBUS, OHIO, A CORPORATION OF OHIO.

MOUNTING FOR WHEELS AND AXLES OF MINE-CARS.

1,215,630.

Specification of Letters Patent. Patented Feb. 13, 1917.

Application filed July 13, 1915. Serial No. 39,559.

To all whom it may concern:

Be it known that I, WALTER A. DORSEY, a citizen of the United States, residing at Columbus, in the county of Franklin and State of Ohio, have invented certain new and useful Improvements in Mountings for Wheels and Axles of Mine-Cars, of which the following is a specification, reference being had therein to the accompanying drawing.

This invention relates to improvements in devices for mounting the wheels and axles on the cars that are used in coal mines; particularly to improvements in such mountings whereby the wearing surfaces will be tightly closed against the entrance of grit or abrasive material, and whereby the axles and the wheels proper will be relieved of strains and wear, and the latter, and the loss caused by them, will be taken by cheap easily replaced parts.

Figure 1 is a cross section of a coal mine car having axles, wheels and mounting devices which embody my improvements;

Fig. 2 is an end elevation of one of the bearing boxes detached;

Fig. 3 is a longitudinal section of a bushing;

Fig. 4 is an end view of the inner end of the same;

Fig. 5 is an inner end view of one of the wheels detached.

In the drawings, 1 indicates the axle. It is formed so as to have no engagement with either of the boxes or with either of the wheels such as to transmit to them thrusts through the car or its load; that is to say, it has none of the usual shoulders or collars in transverse planes immediately adjacent to those of the inner ends of the boxes. This axle can be made with minimum expense by cutting it from round rods of metal of suitable diameter and of the required length. 2, 2 indicate the bearings in which this shaft is loosely mounted, and the latter (although also mounted loosely in the wheels) can, if circumstances compel it to, rotate in the boxes 2. The shaft can be passed freely through the boxes, transversely of the car, when made of material or of the conformation above specified.

Each of the bearing boxes 2 is open at the bottom and has two vertical flanges 7, one in front and one behind the axle and extend-

ing to a line somewhat below it. 8, 8 are bolts that are passed through and lie in apertures in these flanges 7.

Each box has a grooved or chambered enlargement 9, the wall 9^a in front of the groove or chamber, and the wall 9^b behind it being cast integral with the box. The groove or chamber is indicated by 9^c. It, and the walls which bound it, are extended around the upper half of the bearing and are then carried down a short distance, as shown at 9^d, 9^e. The ends of the groove 9^d are spaced apart a distance equal to the diameter of the upper curved part of the chamber. 6, 6 are horizontal flanges or ears cast also integral with the box, and 23 are bolts or rivets which secure these to the car body.

The car may be built in the ordinary way with a frame, bottom and side walls of wood; but I prefer to build it upon a metallic framework such as I have shown in my application, Serial No. 37,086, filed June 29, 1915. 4, 4 indicate the bottom sills of such a metal frame, to which are secured bottom planks 3 and also the side walls 5. The rivets 23 secure the bearing flanges to the metallic sills 4.

11, 11 indicate the wheels, as entireties, these having threads adapted to rest upon the treads 20 of the rails 22 and having flanges 21 which lie inside of the rail treads and bear outwardly against them. Each wheel is cast with a tubular hub 10 having an integral oil chamber 13. This hub is also cast with a wall 24 which completely closes the outer end of the hub so as to prevent the access of sand, grit or other abrasive materials to the wearing surfaces. The inwardly projecting part of the hub has a circular outwardly extending flange 12. This is of such diameter that it can fit in the groove or chamber 9^c in the bearing and lie between the outer flange 9^a and the inner flange 9^b. It serves as the retaining device which holds the wheel in proper lateral position in relation to the car. The closing of the wheel hub by the means of the cap 24 prevents the employment of the usual wheel-retainer such as a pin, bolt or cotter, passing through the end of the axle. The thickness of the wheel-retaining flange 11 is less than the horizontal dimension of the chamber or groove 9^c.

so that the wheel hub is relieved of bearing thrust and of wear at the faces of this flange 12.

When it is desired to put one of the wheels 5 and the adjacent part of the axle in proper position relatively to the bearing, the bolts 8, 8 are withdrawn, and the axle 1 is moved upwardly between the flanges 7, 7 into the position shown in Fig. 1 (or, vice versa, the 10 bearing is let down over the axle), the flange 12 at the same time sliding bodily upward through the straight parts 9^a of the groove or chamber in the enlargement 9 until it is seated loosely in the upper part 9^a of the 15 chamber.

Within each hub there is a bushing 14 which fits around the end part of the shaft snugly, and also fits inside of the wheel hub 10. The inner end of the bushing is formed 20 with projections or lugs 15, preferably of the nature of sections of a circular peripheral flange. The inner end of the wheel hub 10 is correspondingly formed with recesses or sockets 17 of a peripheral length slightly 25 greater than that of the projecting flange sections 15. When the bushing is in place these bushings fit in the recesses in the end of the hub and the bushing and wheel are locked together so that the former rotates 30 with the latter. But the inner end of the bushing bears against the outer vertical bearing face of the box 2. The thrust against the box is first taken by a washer 19, which entirely surrounds the axle, and 35 therefore closes the gap or opening between the flanges 7, 7 and just below the axle.

The lubricant in the chamber 15 passes to the inner wearing surfaces of the bushing through the passages or ports 25, and from 40 these it is carried along the axle to the end thrust surfaces of the bushing.

It will be seen that under ordinary circumstances, and while the car is moving in straight lines, each wheel, with its bushing 45 14, rotates upon the end part of the axle. If at any instant there is a slight cramping of the bushing against the axle, the latter can rotate in its bearings. It will also be seen that if the track swerves from a straight 50 line the flange 21 of the wheel which is on the outer curve begins to bear against the rail tread 20, and the inertia of the car and its load transmits pressure through the box of said wheel to its bushing, and it is then 55 transmitted through the wheel hub and the wheel to the rail. The axle, having no engagement, along axial lines, with either that wheel or its bearing (and, for that matter, having no engagement with the opposite

wheel or its bearing) there is no wear at 60 places other than the wearing surface of the bushing of the wheel on the outer curve. The axle is free to not only rotate but to move endwise, if necessary, both in the 65 wheels and in the bearings. As all of the wear resulting from lateral pressure from the car bearing, and also all of the wear, practically, caused by the rotation of the wheel on the axle, are taken by the bushings, the more expensive elements of the structure 70 are relieved, the inexpensive bushing castings being the only parts that require replacing.

As above remarked, the wheel hub being a tube which is tightly closed at all parts except at its inner end, it is impossible for 75 wearing or abrading particles to gain entrance to the wearing surfaces.

What I claim is:

1. The herein described wheel mounting 80 for a coal mine car, having in combination the car body, the bearing secured thereto, the round rod axle mounted loosely in the bearings and adapted to move longitudinally therethrough, the wheels each loose upon 85 and tightly, inclosing an end of the axle, non-rotary devices carried by the car body engaging with the wheel to hold it longitudinally, and the bushing between the axle and the wheel and interlocking with the 90 latter and bearing against the bearing box.

2. The herein-described wheel mounting 95 for a coal mine car having in combination the body, the bearing box secured thereto having the upper part adapted to rest upon 100 the axle, the downwardly extending axle-guiding and holding flanges and an integral laterally acting wheel retainer, the axle mounted loosely in the bearing box and adapted to be moved transversely to its axis 105 on vertical lines between the said guiding and holding flanges into and out of working position in the bearing box, the wheel loosely mounted on and inclosing the end of the axle and formed with a hub having an 110 integral wheel-retaining device to engage the retaining device on the bearing, and a bushing tube loosely fitted within the hub and interlocking therewith, the hub and bushing being adapted to bear against the box and against the downwardly extending flanges thereon.

In testimony whereof, I affix my signature, in presence of two witnesses.

WALTER A. DORSEY.
